G. P. CARROLL.

SAFETY CONTROLLING MECHANISM FOR COMPRESSING MACHINES.

FILED DEC. 31, 1917.

INVENTOR.

George P. Carroll

UNITED STATES PATENT OFFICE.

GEORGE P. CARROLL, OF HARTFORD, CONNECTICUT.

SAFETY CONTROLLING MECHANISM FOR COMPRESSING MACHINES.

Application filed December 31, 1917. Serial No. 209,670.

To all whom it may concern:

Be it known that I, GEORGE P. CARROLL, a citizen of the United States, residing at Hartford, in the county of Hartford and 5 State of Connecticut, have invented a new and useful Safety Controlling Mechanism for Compressing Machines, of which the following is a specification.

In the construction shown in Figs. 1-5, 10 this application is a continuation of certain matters disclosed in my pending applications Ser. No. 126,019, filed Oct. 16, 1916, entitled Safety construction for refrigerant and other fluid circulating apparatus, and 15 Ser. No. 146,147, filed Feb. 2, 1917, entitled Safety controlling mechanism for compressing machines. This part of my present invention relates to improvements in electrically operated means for controlling 20 the operation of machines that draw in a fluid in a gaseous or vaporous state and at a low pressure, compress it and force it at high pressure into a condenser where the heat of compression is carried away, with 25 or without a resulting liquefaction of the fluid. The compressing machine employed for such purpose more commonly, although not exclusively, is some form of force pump, called a compression machine or compressor, 30 one form of such compressor being herein shown. In the construction of Fig. 6 there is disclosed a detail modification that may be used, by way of substitution for similar parts, in connection with any of the forms 35 of construction set forth in my aforesaid application Ser. No. 146,147. As herein used, the term condenser comprises so much of the apparatus as leads from the discharge valve of the compressing machine and contains 40 the fluid under high pressure, whether in a non-liquefied or in a liquefied state. The fluids circulated in the manner indicated include ammonia, carbon dioxide, sulphur dioxide, air and numerous others. 45 Where the condensed fluid is led from the condenser through a small orifice, so that it can expand and take up heat, the compressing machine is known as a refrigerating machine. But the conditions to which 50 my invention applies also exist in constructions where the fluid is let off from the condenser into containers for transportation and use at a distance. Inasmuch, however, as a refrigerating machine circulating ammonia as the refrigerant is the construction

which is typical of all, my invention will be particularly described in connection with such a machine.

The purpose of my invention is to provide simple, compact and reliable mechanism such that the starting and continued operation of a compressing machine is dependent upon the flow of an adequate supply of condensing water, that the flow of condensing water is automatically so graduated as normally to maintain a predetermined head or condenser pressure and that in case of an excessive operating pressure, tending to become dangerous, arising in the condenser or high pressure side, the operation of the compressing machine will be interrupted. The means for accomplishing these purposes will be hereinafter set forth. There are certain detail improvements of construction that will also so appear.

In the drawings, Fig. 1 is a representation, partially in front elevation and partially in vertical section, of part of the first form of my invention. Fig. 2 is a plan view of the right end of the main lever shown in the preceding figure and its connections, broken away. Fig. 3 is a diagrammatic representation of the structure of the preceding figures in connection with an electrically driven compression refrigerating system. Fig. 4 is a front elevation and Fig. 5 is a plan view of an alternative form of emergency device, with certain related parts, that may be used in place of certain other parts shown in the preceding figures. Fig. 6 is a partial vertical section and a partial front elevation of an alternative form of water reservoir casing and starter that may be used in place of like named parts shown in Figs. 1 and 3.

First considering the construction of Figs. 1-3: A back plate 1, which may be bolted to any convenient vertical surface, has projecting from its front lower part brackets 2 and 3 and from its right hand part a bracket 4. The brackets 2, 3 and 4 are so formed, with a semi-circular concave face in each, as to hold casings 5, 6 and 7, respectively, secured in place by straps 8, 9 and 10, respectively, bolted to their associated brackets. A top plate 11, bolted to the top of the plate 1, projects frontward and has secured to its under side, at the right, an angle bracket 12. A bell crank lever 13 is pivoted to the vertical part of the bracket 12; it has a horizon-

tal arm extending to the right; it has a finger projecting to the left; and it has a depending vertical arm with a catch on the left side at the lower end. A flat spring 14, secured 5 to the horizontal part of the bracket 12, bears upon the upper right end of the horizontal arm of the lever 13 so as to tend to rotate the lever clockwise. An insulating block 15 is secured to the central lower part of the plate 10 11 and has on its under side conducting blocks 16 and 17, spaced a little way apart. From the right end of the block 16 there depends a pivot post 18 and from the block 17 there depends a split sliding contact post 15 19. A switch arm 20 is pivoted to the lower end of the post 18; it is adapted, as shown, when elevated to make a sliding contact between the split parts at the lower end of the post 19; it has an insulated section just to 20 the right of the post 19; it has a right end adapted for engagement with the catch of the lever 13 just below its finger so as to be held in contact with the post 19; and it has a depending handle near to its right end. A 25 pin 21 prevents the arm 20 from dropping too far after disengaging from the post 19. The parts 12-21 constitute the first form of emergency device. The left end of the block 16 has a contact surface on the under side. 30 A contact block 22 is secured to the left under side of the plate 1, but is insulated therefrom.

The casing 5, which is a reservoir casing, at the bottom fits into and rests upon the 35 bracket 2 and is closed on top by a quite flexible diaphragm 23, which may be of rubber, or phosphor bronze, or other suitable material. The central part of the diaphragm 23 supports a disc 24, secured to the lower end 40 of a rod 25. A compression spring 26 surrounds the lower part of the rod 25, bears at its lower end against the disc 24 and bears at its upper end against the under side of a cover casing 27 that is bolted to the casing 45 5, so as to clamp the circumference of the diaphragm 23. The top of the rod 25 is insulated and carries above the insulation a switch 28, adapted to make contacts with the blocks 16 and 22 and to connect them. A 50 collar 29, secured to the rod 25, is adapted to rest on top of the casing 27, as shown, so as to limit the downward movement of the connected reciprocating parts. The thrust of the spring 26 is sufficient to open the 55 switch 28, unless overcome by a stronger pressure of water exerted upward upon the under side of the diaphragm 23. The upward movement of the parts connected with the switch 28 is limited by the disc 24 striking the casing 27 as the switch, which is a leaf switch, closes. The parts 28, 25, 29, 27, 60 26 and 24 constitute the first form of starter.

The casing 6 at the bottom fits into and rests upon the bracket 3 and at its upper left 65 side connects with a horizontal coupling 30,

leading from the lower right side of the casing 5. An outlet passage leads downward through the bottom of the casing 6 and is of the same diameter as the passage from the interior of the casing 5 through the coupling 70 30 into the casing 6. A threaded opening in the top of the casing 6, in axial alinement with the outlet passage of the casing, is closed by a nut plug 31, having a stuffing box recess at the top. A throttling valve 32 has 75 a convex circumference and a flat top and is of a diameter so much less than the diameter of the outlet of the casing 6 that, when the valve is in the position shown at the top of the outlet or is in any lower position, the annular space between the valve and the wall of the outlet will permit of a flow of water about sufficient for the minimum requirements, as will be later explained. A stem 33 is secured to the upper center of the valve 32, passes 80 upward through an opening in the plug 31 and is threaded around the top. Packing 34, in the stuffing box of the plug 31, surrounds the stem 33 and is secured in place by a gland nut 35, having a sleeved extension on top. A compression spring 36 surrounds the extension of the nut 35 and bears at its lower end upon the main part of the nut and at its upper end upon the under side of a collar 37, detachably secured 95 to the stem 33. With the parts in the positions shown, the collar compresses the spring 36, but does not quite strike the extension of the nut 35. If the collar 37 should be forced 100 downward so as to rest upon the extension of the nut 35, the effect simply would be, by means of the stem 33, to force the valve 32 a little further down in the outlet passage of the casing 6, without lessening the flow therethrough. And any further downward 105 movement of the valve 32 would be limited by the collar 37 striking the extension of the nut 35. A sleeved head 38, having a central threaded opening extending from top to bottom, surrounds the threaded top of the 110 stem 33 and is held in a predetermined position of adjustment by a lock nut 39 at its lower end. While the ultimate downward movement of the valve 32 is limited, as just stated, by the collar 37 striking the extension 115 of the nut 35, up to that limit the extent of the possible downward movement of the valve, in the course of operation to be described, may be varied by adjustments up or down of the head 38 and the collar 39. 120 The upward movement of the valve 32 is limited by its striking against the under side of the plug 31. The thrust of the spring 36 is sufficient to force the parts 37, 33, 38 and 32 upward into the position where the 125 valve 32 is in contact with the plug 31, unless overcome by a stronger force applied downward upon the head 38. When the valve 32 is forced upward, even before it reaches the plug 31, the passage through the 130

casing 6 is open to the maximum. The parts 32, 33, 34, 35, 36, 37, 39 and 38 constitute one form of water regulator.

- A pipe 40 is to be connected to lead from a source of cooling water, such as the street mains, into the lower left side of the casing 5 and is controlled by any approved kind of valve or supply means, the valve 41 being a diagrammatic representation of such means.
- 10 The capacity of the pipe 40 and the valve 41 is considerably greater than the capacity of the coupling 30 and the passages leading therefrom, even with the valve 32 in its highest position, so that, however much may be the outflow from the casing 5, the inflow into the casing, under normal conditions of flow when the valve is open, will force upward the diaphragm 23 and the connected reciprocating parts so as to close the switch 28. And this result cannot be affected by any throttling of the flow of water at any point beyond the casing 6.

The casing 7, widely flanged so as to form a shallow chamber on top, at the bottom fits into and rests upon the bracket 4; it has a small vertical passage through its axial center; and it has stops 42 at the top of the passage extending upward within the chamber. A diaphragm 43, preferably of very thin vanadium steel, near its circumference rests upon a ring at the top of the casing 7 and at its circumference rests upon an annular gasket 44, preferably of soft lead, lying on the downwardly sloping rim of the casing just outside the ring. The diaphragm 43 may be forced downward at the center, as shown, until it there rests upon the stops 42. There are passages between the stops 42 so that fluid under pressure may be transmitted back and forth between the space under the diaphragm 43 outside of the stops and the passage at the axial center of the casing. The diaphragm 43 is preferably of vanadium steel because that material remains intact under high pressure and is also freely responsive in its movements to very slight changes of pressure. An upper casing 45 has a flange that fits over so much of the diaphragm 43 as rests upon the casing 7 and the gasket 44 and it has at its extreme circumference an annular tongue enclosing the outer vertical surfaces of the diaphragm and the gasket. By means of bolts 46 the casings 7 and 45 are clamped together at their circumferences and press the edge of the diaphragm 43 and the gasket 44 down upon the casing, the gasket being originally a little higher than the rim of the casing. The casing 45 has in its under side a shallow chamber of equal diameter with the chamber in the top of the casing 7; it has at its axial center a cylindrical chamber extending upward from the shallow chamber nearly to the top;

it has a small threaded passage at its axial center extending through the top; and it has a space to the lower right hand side of the cylindrical chamber from which a horizontal shaft passage extends through the rear wall. A reciprocating member 47 has a flange at the lower end resting upon the center of the diaphragm 43 and of a diameter greater than that of the stops 42; above its flange it is adapted to reciprocate within the lower end of the cylindrical chamber in the casing 45; and it has in the part so reciprocating a transverse passage extending from left to right. Just as the stops 42 limit the downward movement of the center of the diaphragm 43 and of the member 47 resting upon the diaphragm, so the upward movement of the member would be limited, in case of extremely high pressure on the under side of the diaphragm, by its flange striking the wall of the casing 45 around the lower end of the cylindrical chamber therein. A heavy compression spring 48 occupies the upper end of the cylindrical chamber in the casing 45 and it bears, at the lower end, upon the top of the member 47 and, at the upper end, upon the head of a threaded bolt 49 passing upward through the passage in the top of the casing 45. The end of the bolt 49 above and outside of the casing 45 has a square wrench section whereby the bolt may be turned up or down and it is held in any desired position by a lock nut 50 just above the top of the casing 45. It is evident that, upon loosening the nut 50, the bolt 49 may be screwed downward so as to increase the thrust of the spring 48, or it may be screwed upward so as to decrease the thrust. A cap 51 screws around the threaded top of the casing 45, which is of reduced diameter, and over the nut 50 and the exposed end of the bolt 49. Projecting to the right of the lower end of the cap 51 is a lug with a transverse hole through it and projecting to the right of the top of the casing 45, just under the former lug, is a similar lug with a transverse hole through it. A wire may be passed through the holes of the lugs of the cap 51 and the casing 45 and then sealed, as shown, so as to prevent any tampering with the bolt 49 and the nut 50 after they have been adjusted. A rock shaft 52 is journaled at its rear end in the front end of a support 53, extending frontward from the plate 1; it enters the rear wall of the casing 45 through a stuffing box gland nut 54; it has secured to its front end within the casing a short lever 55 that has its free end within the recess of the member 47. A long lever 56 is secured to the shaft 52 between the nut 54 and the support 53 and at its outer end is adapted to bear successively upon the head 38 and

the under side of the outer end of the horizontal arm of the lever 13. The parts 46—56 constitute one form of controller.

From the casing 6 condenser water piping 57 leads downward into the lower left end of a condenser tank 58, coils upward therein and emerges from its upper left end. A pipe 59 connects the casing 7 with the top of the tank 58. A gage 60 indicates the 10 pressure in the tank 58 and certain of its connected piping. From the under side of the tank 58, a liquid pipe 61 leads to an expansion valve 62, preferably of the automatic type. An expansion chamber, evaporator or expansion coil 63, as it is variously called, leads from the valve 62 and discharges into a suction pipe 64. A compressor 65 leads from the pipe 64 and discharges into a hot gas pipe 66, which leads into the 20 top of the tank 58 and has connected with it a relief valve 67. The valve 67 in practice has its discharge leading into the atmosphere outside of the plant. The old practice was to set a relief valve, such as the 25 valve 67, to discharge at a pressure of 300 pounds. The recent and better practice requires such a valve to begin to open at 250 pounds pressure and to be fully open at 275 pounds pressure. The piping 57, after 30 emerging from the tank 58, enters the water jacket of the compressor 65; and from the opposite upper part of the water jacket a pipe 68 discharges to waste.

From a generator 69, a wire 70 leads to the 35 upper one of a series of contacts 71 connected to one another by divisional or sub-resistances. An arm 72 is pivoted near its left end, but is insulated from the pivot; it is pivoted near its center to a solenoid core 40 73, but is insulated therefrom; and at its right end it operates, upon the energization of the core, to make contact with the contacts 71, in ascending order, so as to cut out the resistances between the contacts successively. 45 A dash pot device 74 is pivoted to the left end of the arm 72 and is operative to retard the upward movement of the right end of the arm. From the arm 72, near its pivot, a wire 75 leads to an electric motor 76, connected for driving the compressor 65; and from the motor a wire 77 leads through a point 78 back to the generator 69. From the wire 70, a resistance 79 leads to a branch wire 80, which leads to the block 17. From 50 the block 22, a wire 81 leads to a solenoid winding 82, adapted to energize the core 73. From the winding 82 a wire 83 leads to the point 78. The parts 71, 72, 73, 74 and 82 constitute one form of starting rheostat, 55 commonly termed a self starter, any such rheostat being adapted to close the circuit of a motor, but tending to open the circuit. I am not to be understood as being limited to any particular form of such rheostat. The 60 compressor 65 represents a compressor of 65

any type and of any capacity and is one form of forcing means for forcing fluid into a condenser.

The method of operation is as follows: Let it be assumed that 160 pounds is the desired head pressure to be maintained, as will be indicated by the gage 60. In the cooler months of the year, when the condensing water is cool, and with the compressor 65 operating at a low back pressure, that is to 70 say with an adjustment of the valve 62 such that the gas coming from the pipe 64 is of low pressure, so as to result in a minimum load for the compressor, the quantity of water flowing past the valve 32 in the position shown will be about sufficient to maintain a head pressure of 160 pounds, as will be explained. If the quantity of water flowing past the valve 32 is a little too much, the only effect will be that, under the minimum 80 requirements indicated, a little lower head pressure will be maintained and a little more condensing water will be used than will be strictly necessary. And such a condition could be easily rectified by substituting a 85 valve 32 of larger diameter. If on the other hand, the quantity of water flowing past the valve 32 in the position shown is not enough for the minimum requirements, the only effect will be that the valve will be lifted 90 automatically, as will be explained, sufficiently to maintain a predetermined head pressure, a little earlier than otherwise. It is also assumed that the condenser is of sufficient capacity to cool the hot gas discharged 100 through the pipe 66 into the tank 58 under the maximum requirements of operation, that is to say in the heat of summer, with the condensing water at the warmest, and with a high back pressure. Then, as also assumed, 105 the passages through the coupling 30 and the casing 6, with the valve 32 sufficiently lifted, are sufficient to transmit the maximum quantity of water required by the condenser. 110

Now assume that the compressor 65 is to be operated under conditions requiring the minimum flow of condensing water. On opening the valve 41, water rushes into the casing 5 and in part flows through the 115 coupling 30, the casing 6 and the piping 57, so as to cool the interior of the tank 58, and discharges at the outlet end of the pipe 68. But the part of the water entering the casing 5, and unable to flow away, presses upward upon the diaphragm 23 so as to close the switch 28. Thereupon a current passes from the generator 69 through the parts 70, 79, 80, 17, 19, 20, 18, 16, 28, 22, 81, 82, 83, 78 and 77 back to the generator so as to energize the core 73. Consequently the arm 72 makes contact with the contacts 71, cutting out successive resistances, until the full current passes from the generator 69 through the parts 70, 71, 72, 75, 76, 77 and 78 back 130

to the generator and, as a result, the motor 76 and the compressor 65 are running at full speed. The compressor 65 now draws expanded ammonia from the pipe 64 and 5 forces it under high pressure through the pipe 66 into the tank 58. The temperature and pressure in the tank 58 consequently tend to rise very greatly, but this tendency is counteracted by the cooling effect of the 10 water flowing through the piping 57 so that the ammonia in the lower part of the tank 58, in consequence of pressure and cooling, is liquefied. With the withdrawal of expanded ammonia from the pipe 64 into the 15 compressor 65, the pressure in the chamber 63 tends to drop, so that liquid ammonia from the tank 58 and the pipe 61 passes the valve 62, and, vaporizing, produces the desired refrigerating effect in the compartment, not shown, which encloses the chamber. The same results would follow with a 20 plurality of expansion chambers in parallel, each provided with its own expansion valve. When it is desired to terminate the period 25 of refrigeration, the valve 41 is closed, so that no more water can enter the casing 5. But as water still flows away through the piping 57, a vacuum tends to be created under the diaphragm 23 and the spring 26 thereupon opens the switch 28. The core 30 73 being thus de-energized, the arm 72 makes contact with the contacts 71 in descending order, throwing in the successive resistances, until finally all current is shut 35 off and the motor 76 and the compressor 65 begin to slow down and finally stop. But while the motor 76 and the compressor 65 are slowing down, after the current has been shut off, the compressor is still discharging 40 hot gas into the condenser. If, under such circumstances, the flow of water through the piping 57 had been simultaneously shut off, the tendency would have been to create a head pressure high enough to open the valve 45 67 and thus to release some of the ammonia charge, or, if the valve 67 were omitted, to produce a dangerous pressure in the system. But this tendency, in my construction, is counteracted by the provision of the reservoir, 50 consisting of the part of the pipe 40 to the right of the valve 41, the parts 5, 23, 30 and 31 and the upper part of the casing 6, draining into the lower part of the casing 6 and the piping 57, being of any necessary 55 or proper capacity and continuing to supply water to the piping between the time when the current is shut off and the time when the motor 76 and the compressor 65 come to rest. It also will happen from time to 60 time that, while the valve 41 is open, there will be an accidental interruption of the flow of water entering the reservoir. Here, again, the tendency would be to produce a high or dangerous pressure. But such an 65 interruption, in my construction, has the

same results, in shutting off the current and in providing from the reservoir a supply of water until the motor 76 and the compressor 65 come to rest, as does the closing of the valve 41. But, in this case of an accidental 70 interruption of the water supply, when the water again flows into the casing 5, the upward pressure on the diaphragm 23 closes the switch 28 and automatically starts the motor 76 and the compressor 65. It is also 75 to be noted that whenever a flow of water is admitted to the reservoir, water begins to flow into the piping 57 before pressing upon the diaphragm 23, thus making certain some cooling of the condenser before it begins to 80 receive hot gas.

Now suppose, as is more frequently the case, that the flow of water past the valve 32 in the position shown is insufficient to keep the head pressure down to 160 pounds. 85 Then, as the pressure indicated by the gage 60 rises, the pressure of fluid transmitted through the pipe 59 upon the diaphragm 43 forces the diaphragm, the member 47 and the lever 55 upward, in opposition to the 90 spring 48, so as to rotate the shaft 52 and the lever 56 slightly upward. The effect is that, as the lever 56 tends to cease pressing on the head 38, the spring 36 tends to act on the collar 37 so as to lift the valve 95 32. More water thereupon tends to flow to the condenser, the pressure on the diaphragm 43 tends to lessen and the spring 48 tends to force downward its controlled parts so as to depress the valve 32 and to diminish the 100 flow of water past it. An equilibrium is thus established so as to maintain the head pressure of 160 pounds. The primary adjustment is made by means of the bolt 49 and the nut 50 and the secondary adjustment, so as to maintain the particular head 105 pressure desired, is made by turning the head 38 and the nut 39 up or down. After the primary adjustment had been made, the cap 51 and the casing 45 would properly be 110 sealed, as has been indicated, and then any operator of the machine would be free to make such secondary adjustment as might be desired. Where the valve 32 acts to graduate the flow of condensing water, the 115 operation in all other respects upon opening or closing the valve 41 and upon a cessation of the water supply is the same as has been described.

Such is the normal course of operation. 120 But it sometimes happens that the condenser piping gets foul, or non-condensable gases find lodgment in the condenser, or it develops as the summer comes on that the condenser is too small or is improperly designed, so 125 that even the maximum flow of condensing water is insufficient to prevent an abnormal head pressure. Suppose that the water regulator and the controller are so adjusted that the head pressure is normally main- 130

tained at 160 pounds and that the lever 56 bears upon the lever 13 at a pressure of 190 pounds. Then, when the gage 60 shows a pressure in excess of 160 pounds and the lever 56 is in a position somewhere between the head 38 and the horizontal arm of the lever 13, there is sufficient warning of an abnormal condition in the system that should be rectified. If this warning is neglected, 10 on the condenser pressure rising to 190 pounds, the lever 56 trips the lever 13 so as to release the arm 20 and to break its contact with the post 19. This breaking of contact has the same slowing down and stopping effect as does the opening of the switch 28. When the abnormal condition in the system has been rectified, the handle of the arm 20 is used to close the arm, the lever 13 at the same time being manually turned 15 counter-clockwise, for an instant, in opposition to the spring 14.

With the exception of excessive pressures developing in the compressor itself, my construction prevents the development of all excessive pressures in any part of the high pressure side of the system consequential upon the operation of the machine. But an excessive pressure in a refrigerating system, that may ultimately result in an explosion, may arise from external causes. In case of a fire involving the plant, the lever 56 would trip the lever 13 so as to stop completely the process of refrigeration, if the compressor 65 should then be running, and, if the pressure should rise to 250 pounds, which corresponds to a temperature of 110 degrees F., the valve 67 would begin to blow off, letting the ammonia escape into the atmosphere. It is, of course, obvious that where the summer atmospheric temperature may exceed 110 degrees, the valve 67 must be set to open at some limit higher than 250 pounds.

Next considering the construction of Figs. 45 4 and 5, intended, if desired, as a substitute for certain parts shown in Figs. 1-3: A block 84, corresponding to the block 16, is only of sufficient length to serve as a contact for the right end of the switch 28. All 50 parts of the plate 11 and the block 15 to the right of a vertical line coincident with the right edge of the block 54, and also all connected electrical parts, are to be understood as omitted. A bracket 85 may be 55 screwed or bolted to the plate 1 and it extends at the top frontward so as to support an insulated contact 86, with which the wire 80 is connected. A rock shaft 87 is 60 journaled in an opening through the bracket 85 but is insulated therefrom and carries at 65 its end in front of the bracket a contact arm 88, normally in a position of sliding contact with the contact 86. Secured to but insulated from the bracket 85 is a spring contact 89, operative to keep in contact with

the arm 88 in whatever position the latter may be. A wire 90 connects the contacts 89 and 84. Secured to the end of the shaft 81 back of the bracket 85 is a weight arm ending in a globular weight 91 at the top and having projecting to the right of the shaft an upper limit arm 92 and a lower limit arm 93. A pin 94 projects from back of the bracket and, when the weight is to the right of the vertical center of shaft 87, in a position, as shown, with the arm 88 in contact with the contact 86, the pin prevents the weight from falling further to the right. Another pin 95 projects from the back of the bracket 85, at a position to the left of the pin 94, and prevents the weight from falling too far to the left. An actuating pin 96 projects frontward from the left end of the lever 56. When the lever 56 is sufficiently lifted, the pin 96 engages the arm 92 so as to throw the weight 91 to the left of the vertical center of the shaft 87, as far as the pin 95 permits, but sufficiently for the arm 88 to break connection with the contact 86. When the lever 56 subsequently descends, the position of the arm 93 is such that, after a certain movement downward, the pin 96 engages the arm 93 so as to throw the weight 91 to the right of the vertical center of the shaft 87, as far as the pin 94 permits, but sufficiently for the arm 88 again to make connection with the contact 86. With the wire 80 connected as shown in Fig. 3 and with the lever 56 operating as just described, it is apparent that, as before, the motor 76 and the compressor 65 are automatically stopped in case of excessive pressure and that, furthermore, when the condenser pressure drops back to normal, their operation is automatically resumed. This modified construction may be preferred in case of a thermostatically controlled motor and compressor, where on a drop of pressure the thermostat resumes control of the system.

Finally considering the construction of Fig. 6: The pipe 40 leads into the lower left side of a reservoir casing 97 and the coupling 30 leads from the lower right side of the casing. Surrounding and covering an opening in the top of the casing 97 is an expanding and contracting cylindrical bellows 98, with an undulated or zigzagged circumferential side wall and a flat head. The bellows 98 may be of brass or copper, or it may be of vanadium steel, copper plated or Sheradized or otherwise protected against corrosion; and, if constructed of any such material, of a suitable thinness, it is sensitive to pressure changes so as to permit the head to move up or down along the axis. Secured at its lower end to the flat head of the bellows 98 is a rod 99, adapted to reciprocate in a guide 100 and carrying above its insulated top the switch 28. A helical coil 130

pression spring 101 surrounds the rod 99, at its upper end bears upon the under side of the guide 100 and at its lower end bears upon the upper side of a nut 102, threaded upon the rod and secured in place by a lock-nut 103. The spring 101 always tends to open the switch 28, but yields to an upward movement of the head of the bellows 98, in response to the pressure of water on the under side thereof, so as to close the switch. This last construction may be used as a substitute for the parts 5, 23, 24, 25, 26, 27 and 29 already considered. The circumstances under which the switch 28, in both constructions, is opened, and the operating effect of actuation, are precisely the same.

I am not to be understood as being limited to any particular kind of water reservoir and to any particular means whereby, on a rise 20 of the liquid level therein, the power is turned on to the forcing means and whereby, on a fall of such level, such power is turned off. Nor am I limited to any particular kind of water regulator, or controller, or emergency device. It is to be noted that the water regulator and the emergency device are controlled, through the medium of the controller, broadly speaking, by the head pressure of the apparatus. The starting rheostat composed of the parts 71, 72, 73, 74 and 82 is to be taken as representative of the starting rheostats of all electric motor and compressor combinations, the compressors in such combinations having refrigerating capacities ranging from a fraction of a ton up to 300 tons or over. In nearly all such rheostats, the closing of a branch circuit operates, by means of mechanism usually of much greater complexity, to cut out successive resistances and to turn on the full current and the breaking of the branch circuit, by permitting an opening tendency to have full effect, operates to shut off the current completely.

45 What I have invented and what I desire to have protected by Letters Patent is expressed in claims as follows: I claim:

1. In a condensing apparatus, a gas condenser, a conduit for supplying water to cool the condenser, a valve positioned in the conduit, means operative on the valve with an increase of condenser pressure to increase the flow through the conduit and with a decrease of such pressure to decrease such flow, two electric conductors, and means operative with a rise of water pressure in advance of the valve to connect the conductors and on a fall of such water pressure to disconnect them.

60 2. In a condensing apparatus, a gas condenser, a water reservoir, an outlet conduit leading from the reservoir downward to the condenser, a valve positioned in the conduit, means operative on the valve with an increase of condenser pressure to increase the

flow through the conduit and with a decrease of such pressure to decrease such flow, two electric conductors, and means operative on a filling of the reservoir by water under pressure to connect the conductors and on a fall of such water pressure to disconnect them.

3. In a condensing apparatus, a gas condenser, a conduit for supplying water to cool the condenser, a valve positioned in the conduit, two electric conductors, an emergency switch for connecting and disconnecting the conductors, means operative on the valve with a decrease of condenser pressure to decrease the flow through the conduit, with an increase of such pressure to increase such flow and upon a predetermined increase of such pressure to open said switch, a third conductor adapted for connection in series with one of the former conductors, a second switch for so connecting the third conductor or disconnecting it, and means operating on a rise of water pressure in advance of the valve to close the second switch and on a fall of such water pressure to open it.

4. In a condensing apparatus, a gas condenser, a conduit for supplying water to cool the condenser, a valve positioned in the conduit, two electric conductors, an emergency switch for connecting and disconnecting the conductors, means operative on the valve with a decrease of condenser pressure to decrease the flow through the conduit, with an increase of such pressure to increase such flow, upon an abnormal increase of such pressure to open said switch and upon a return of such pressure to normal to close the switch, a third conductor adapted for connection in series with one of the former conductors, a second switch for so connecting the third conductor or disconnecting it, and means operating on a rise of water pressure in advance of the valve to close the second switch and upon a fall of such water pressure to open it.

5. In a condensing apparatus, a gas condenser, a conduit for supplying water to cool the condenser, a valve device controlling the conduit, two electric conductors, an emergency switch for connecting and disconnecting the conductors, and a pivoted lever device having a free lever end and movable back and forth between the valve device and said switch and operative on the valve device with a decrease of condenser pressure to decrease the flow through the conduit, with an increase of such pressure to increase such flow and upon a predetermined increase of such pressure to open said switch.

6. In a condensing apparatus, a gas condenser, a conduit for supplying water to cool the condenser, a valve device controlling the conduit, two electric conductors, an emergency switch for connecting and dis-

connecting the conductors, and a pivoted lever device having a free lever end movable back and forth between the valve device and said switch and operative on the 5 valve device with a decrease of condenser pressure to decrease the flow through the conduit, with an increase of such pressure to increase such flow, upon an abnormal increase of such pressure to open said switch 10 and upon a return of such pressure to normal to close said switch.

7. In combination, a condenser, electrically operated forcing means for forcing fluid into the condenser, conductors adapted to be connected in series and to be disconnected, 15 means permitting the operation of the forcing means when the conductors are so connected and preventing such operation when they are disconnected, a gravity switch on being tilted forward disconnecting the conductors, and a controller controlled by the head pressure and tilting the switch forward upon a predetermined rise of head pressure.

20 8. In combination, a condenser, electrically operated forcing means for forcing fluid into the condenser, conductors adapted to be connected in series and to be disconnected, 25 means permitting the operation of the forcing means when the conductors are so connected and preventing such operation when they are disconnected, a gravity switch on being tilted forward disconnecting the conductors and on being tilted 30 backward connecting them again, and a controller controlled by the head pressure and tilting the switch forward upon a predetermined rise of head pressure and backward upon a predetermined fall of head pressure.

35 9. In combination, a condenser, water

40 supply piping therefor, electrically operated forcing means for forcing fluid into the condenser, conductors adapted to be connected in series and to be disconnected, 45 means permitting the operation of the forcing means when a supply of water under pressure is available for the piping and when the conductors are so connected and preventing such operation, either upon a fall of the water pressure or if the conductors are disconnected, a gravity switch on being tilted forward disconnecting the conductors, and a controller controlled by the head pressure and tilting the switch forward upon a predetermined rise of head 50 pressure.

55 10. In combination, a condenser, water supply piping therefor, electrically operated forcing means for forcing fluid into the condenser, conductors adapted to be 60 connected in series and to be disconnected, means permitting the operation of the forcing means when a supply of water under pressure is available for the piping and when the conductors are so connected and 65 preventing such operation either upon a fall of the water pressure or if the conductors are disconnected, a gravity switch on being tilted forward disconnecting the conductors and on being tilted backward connecting them again, and a controller controlled by the head pressure and tilting the switch forward upon a predetermined rise of head pressure and backward upon a predetermined fall of head pressure.
